UNITED STATES PATENT OFFICE.

HERBERT LUTZ, OF HAMILTON, ONTARIO, CANADA, ASSIGNOR OF ONE-HALF TO GEORGE MORRIS, OF HAMILTON, ONTARIO, CANADA.

REFILLABLE-FUSE CARTRIDGE.

1,282,606.

Specification of Letters Patent. Patented Oct. 22, 1918.

Application filed April 23, 1918. Serial No. 239,307.

To all whom it may concern:

Be it known that I, HERBERT LUTZ, residing at Hamilton, in the Province of Ontario and Dominion of Canada, have invented a new and Improved Refillable-Fuse Cartridge, of which the following is a specification.

This invention has reference to certain improvements in inclosed or cartridge fuses of the refillable type involving the use of a casing of insulated material and wherein the fusible element is removably contained so that the said element may be readily replaced for a new fuse, whenever it is blown. Primarily, my invention seeks to provide a fuse cartridge of the character stated, of a simple and inexpensive construction, in which the parts are especially designed to provide a quick refillable fuse having contacts at the outer or cap ends of the casing designed for keeping the contacts cool and presenting a long fuse space.

My invention in its complete make-up embodies an improved construction of casing end caps, the knife contacts and the engaging ends of the fuse element whereby a quick, convenient and effective interlocking of the parts may be obtained and the said parts arranged to produce a compact cartridge in which the possibility of the fusing element and the interlocking end connections becoming disengaged or out of proper operative electrical contact is reduced to the minimum.

My invention also embodies certain details of construction and combination of parts, all of which will hereinafter be fully explained, specifically pointed out in the appended claims and illustrated in the accompanying drawings, in which:

Figure 1 is a perspective view of my improved quick refillable fuse cartridge.

Fig. 2 is a longitudinal section thereof, the parts being at their operatively connected position.

Figs. 3 and 4 are cross sections thereof taken on the line 3—3 and 4—4 respectively on Fig. 2.

Fig. 5 is a perspective view of one of the knife contacts and an adjacent end of the casing to which the contact is connected, when the parts are assembled.

Fig. 6 is a detail diagrammatic longitudinal section of one end of the cartridge casing the knife contact and the cap that join

with the said casing end, the several parts being positioned to indicate the manner in which the adjacent fuse end may be interlockably connected therewith.

Fig. 7 is a detail longitudinal section of one end of a casing and a modified construction of a small knife blade contact and the co-operating casing cap.

Fig. 8 is a perspective view of the said modified form of contact. 65

Fig. 9 is a detail view of a modified form of the fuse element hereinafter referred to.

Fig. 10 is a detail view of the fuse strip.

In carrying out my invention, I provide a cartridge body in the nature of an open 70 ended tube or casing 1, of suitable insulating material, provided along its length with a mica covered sight opening 10 for inspecting the fuse.

In shaping up the tubular casing 1, each 75 end thereof has a sector section cut out to thereby form longitudinal extensions 11—11, each having a slotway 12 whose inner ends merge with oppositely disposed lateral depressions or notches 13—13 that constitute 80 parts of the interlocking elements presently more fully described.

The fuse element in my construction of fuse cartridge may consist of a thin metal strip 2, as shown, or it may be formed of 85 wire as shown in Fig. 9, and the said element extends diagonally across the fuse chamber to thereby present a long fuse space.

The ends of the fuse 2, when formed of a metal strip, each have an aperture 20, but 90 when the fuse is formed of wire, the said fuse ends terminate in eye loops, the said apertures 20 or eye loops being provided for engaging with the fuse fastening screws 6—6, presently again referred to. 95

By referring more particularly to Fig. 2 of the drawings, it will be noticed that, when the parts are assembled for use, the ends of the fuse extend through long slots or openings 12 in the casing extensions 11 and engage with the knife blade contacts 3, of which there is one for each end of the casing. 100

The knife blade contacts 3, one of which is shown in detail in Fig. 5, each include a member 30 that constitutes an end extension that projects from the longitudinal axis of the casing 1 and is provided with the usual lateral recess 30^a for supporting the cartridge in the usual operative position. 105

The knife blade contact 3 also includes an 110

angled member 31 adapted for seating in the end grooves 12^a—12^a of the casing and a fuse contacting member 34.

Contact member 34 has a beveled notch 34^a in its end and the notches 34^a of the members 34, when the parts are assembled, oppose undercut beveled notches 14—14 in the ends of the casing 1, as is clearly shown in Figs. 2 and 6 of the drawings, and for the reason 10 presently explained.

The contact members 34 of the blades 3 are of sufficient width to seat upon the opposing bearing edges 12 of the casing extensions 11—11 and the said members each 15 have inwardly bent flanges or lugs 35—35 for interlockably engaging with the notches 13 in the casing extensions, when the parts are assembled as in Figs. 1 and 2.

4—4 designate cup-shaped caps that fit 20 over and form end closures for the tubular casing 1 and each of said caps 4, when the contacts 3 are of the form shown in Figs. 1, 2, 3 and 5, have slots 40 for slipping over the bracket-like extensions 30 of the said 25 contacts. When, however, the contacts are adapted for use on small fuses, the said contacts are shaped without the bracket extensions 30, as shown in Figs. 8 and 9, and when the contacts are thus shaped, the slots 30 40 in the caps 4, are omitted, but in either of the forms stated, the said caps 4 have one or more vent apertures 44, as shown.

The fuse contacting face of each knife blade 3 has a threaded aperture 36 for receiving the clamp screws 6 that pass through the apertures 45 in the caps 4 and the apertures or eyes 36 in the fuse strip or wire.

8—8 designate the screws that secure the 40 caps to the casing end.

From the foregoing description taken in connection with the drawings, the complete construction and the advantages of my improved fuse cartridge will be readily apparent to those skilled in the art to which my invention relates.

It is to be noted that by forming the ends 50 of the casing, the blade contacts, the end caps, and securing the latter by screws 8—8, as described and shown, when a fuse is disrupted by overload or overheating, by simply removing the screws 8—8, the caps with their respective blade contacts, the attached fuse portions may be readily pulled 55 out from the casing end and the fuse portions pulled from their contacts 3 and the caps 4 by removing the clamp screws 6.

To refill the cartridge, a new fuse strip or wire is attached to one of the caps 4 and 60 its coöperating contact 3 and the said strip or wire is then projected through one end of the casing and the cap to which it is attached to then made fast to the said casing end.

65 The free end of the fuse strip or wire,

when the other end has been made fast, as stated, is projected through the other end of the casing, as is indicated in Fig. 6, in position for being applied to the blade contact 3 for that end, it being obvious that 70 the undercut notch 14 on the casing end allows the projected end of the fuse 2 to bend up and back, see dotted lines Fig. 6, when fitting the member on that end.

After the member 3 has been applied, as 75 stated, the end of the fuse is bent down between the notch 34^a and onto the contact bearing 34, after which the cap 4 is slipped over the casing extension 11, the member 34 and the said fuse end, the latter and the 80 member 34 being interlocked by applying the screw 6 which clamps the fuse end between the contact 34 and the cap, as is clearly shown in Figs. 2 and 3. Cap 4 is then made secure on the casing 1 by applying the screw 8.

What I claim is:

1. In a refillable fuse cartridge, a tubular casing having end extensions, each of the said extensions being longitudinally slotted, a 90 contact member for each extension, the said extensions and the contact members having interlocking portions, a cap plate insertible over each casing extension and the contact member, a fusible element having its end 95 extended between the caps and their respective contact member, means for clamping said caps and their respective contact members and the fusible element ends, and other means for securing the caps onto the 100 casing.

2. In a refillable fuse cartridge, an insulated casing open at both ends and having each end formed with an extension longitudinally slotted, the two extensions being reversibly arranged whereby the opening in the said extensions face in diametrically opposite directions, a contact member for each extension, the latter and their respective contact members having 110 interlocking portions, a diagonally projected fuse element having its end projected for engaging the opposite end contacts, end caps that form the closures for the casing ends, means for clamping the ends of the 115 fusible elements between the contacts and the caps and other means for securing the caps over the casing end.

3. A refillable fuse cartridge comprising a tubular shell of an insulating material and having longitudinally slotted end extensions, the said end extensions having bearing faces parallel with their slots and oppositely disposed vertical guide ways in their outer ends, the extensions being reversibly arranged whereby their slot-ways will be projected in diametrically opposite directions, a knife blade contact for each end extension of the shell, said blade contacts each including a member for seating on the bearings 120

130

- of the slotted shell end extensions, an angled portion whose opposite ends are adapted for slidably engaging the vertical guide ways in the said extensions and a bracket portion that extends outwardly from the shell in the longitudinal axis thereof, a cross over fuse member whose ends are extended to rest on the blade contact members, a cap member for each end of the tubular shell,
- 5 the said cap members each having a central slot for the bracket extensions of the blade contacts at their respective ends, means for clamping the said ends of the fuse members between the knife blade contacts and the
- 10 caps, and other means for securing the caps to close over the open ends of the shell.
4. A refillable fuse cartridge that comprises the following elements in combination, a tubular shell of insulating material formed with end extensions, the said extensions being longitudinally slotted whereby opposite side bearings are formed on said extensions, the two extensions being projected diametrically opposite each other, the
- 15 bearings on each extension having transversely aligned notches at their inner ends,
- the open ends of the extension being formed with oppositely disposed vertical guides, a knife blade contact for each end extension, said contact each including a bearing portion for seating on the side bearings of their relatively respective extensions, each of the said portions having inturned members for interlocking with the sockets in their respective extensions, said knife blade contacts also including angled portions for slidably engaging the vertical guides in the end extensions, a cross over fuse member whose ends are extended for resting on the
- 20 blade contact member, a cap member for each end of the tubular shell, means for clamping the said ends of the fuse member between the knife blade contacts and the caps, the adjacent ends of the tubular shell and the knife blade contacts having opposing beveled notches, and means for securing the caps to close over the open ends of the tubular shell.
